UNITED STATES PATENT OFFICE

172,694

TOY GUN FOR A BICYCLE HANDLEBAR

Serge Abagoff, Burbank, Calif.

Application January 16, 1953, Serial No. 23,162

Term of patent 14 years

(Cl. D34—15)

To all whom it may concern:

Be it known that I, Serge Abagoff, a citizen of the United States, residing at Burbank, State of California, have invented a new, original, and ornamental Design for a Toy Gun for a Bicycle Handlebar, of which the following is a specification, reference being had to the accompanying drawing, forming a part hereof.

Fig. 1 is a perspective view of a toy gun for a bicycle handlebar, showing my new design as it would appear when in normal use, the broken line disclosure of the handlebar being included for convenience of illustration only.

Fig. 2 is a front elevational view of the toy gun shown in Fig. 1.

I claim:

The ornamental design for a toy gun for a bicycle handlebar, as shown and described.
